MEANS FOR CORRELATING DRILL BIT
SHARPENING AND GAUGING MECHANISM

James F. McCarthy, Jr., Wallace, Idaho

Application October 14, 1942, Serial No. 461,965

5 Claims. (Cl. 90—16)

My invention relates to improvements in means for correlating drill bit sharpening and gauging mechanism, and more particularly to machinery of the type used to recondition dulled detachable rock drill bits by the known "hot-milling" processes of the art.

As shown in my earlier Patent No. 2,268,714, issued January 6, 1942, mechanism for hot-milling detachable rock drill bits has been provided in which, at a single station, the dulled bit is presented to a sharpening means and subsequently to a gauging means. In that earlier device the sharpening and gauging means were substantially fixed, and the bit presenting means was movable to alter the nature of the presentation of the bit. While the arrangement disclosed in the patent above referred to was satisfactory, it did place limitations upon the operation of the machine that I have now found can be obviated without difficulty and with a subsequent material enlargement of the utility and operability of the whole mechanism.

The problem which I here solve actually arises in the bits to be sharpened and gauged. Rock drill bits comprise the shape of a hollow cylindrical shank, usually internally threaded for attachment to a drill bar, having a plurality of flaring wings that are angularly disposed to each other and overhang the cylindrical shank. The impact faces of these wings are provided with cutting edges that extend radially of the bit and terminate on the outer end of the wings, the face of which is arcuate and has a rearwardly decreasing taper to permit disposal of rock cuttings from the cutting face during the drilling operation. When a bit is used the cutting edges dull and the taper on the end of the wings is altered or destroyed. Consequently a reconditioning of such a dulled bit entails the formation of new cutting edges on the wings and the resurfacing of the gauge ends of the wings. Each time that a bit is reconditioned it loses height and decreases in the radial dimension of the bit wings. It follows, therefore, that in the later stages of a series of reconditionings not only must the slope of the bit tooth be altered to prevent too great a removal of body metal, but the angle of undercut on the end of the wings of the bit must be more erect or more nearly parallel to the axis of the bit to prevent weakening of the threaded skirt if the gauging device is permitted to remove metal therefrom. Since the bits decrease in diameter somewhat in proportion to their decrease in height it is important that mechanism for reconditioning them be adapted

to be adjusted to these conditions. It is also important that the adjusting operations of the sharpening and the gauging means be tied together in their adjustments so that the altering of the operation of one is translated into a similar and correlated altering of the operation of the other. To the solution of these problems my invention particularly pertains.

Having in mind the defects of the prior art bit conditioning mechanism, it is an important object of this invention to provide machinery for reconditioning rock drill bits which is easily adjusted to meet varying conditions resulting from the necessity of conditioning bits in various stages of their useful life.

Another object of my invention is the provision, in machinery of the type described, of apparatus for correlating the adjustment of the elements of the reconditioning mechanism, 20 which apparatus operates automatically to set the mechanism although the adjustment action may be applied to only one element of the conditions being accommodated.

A still further and more specific object of my invention is to provide, in machinery of the class described, a link mechanism between the sharpening and gauging means whereby, when the sharpening means is set to properly sharpen a drill, the gauging means, through the action of 30 the link mechanism, will be set to properly gauge the same drill bit.

The foregoing objects and others ancillary thereto I prefer to accomplish as follows:

According to a preferred embodiment of my invention, I mount a pair of milling cutters in the path described by the swinging movement of a drill bit that is carried upon a pivoted arm tool holder. One of these milling cutters has a pointed nose which shapes the cutting edge and sloping sides of adjacent drill bit teeth or wings. In the case of drill bits having a plurality of teeth the bit is presented to the sharpening miller several times so that both sides of each tooth are surfaced and all the cutting edges of 40 the bits are sharpened. Upon completion of the sharpening operation the bit is cut to a gauge diameter by being presented to the gauging miller in its path of swinging movement upon the tool holder or arm. The gauging cutter has a sloping surface which receives the gauge ends of the teeth and surfaces them to properly shape the tooth for clearance and cutting.

Each of the milling cutters is rotated by means, generally an electric motor, that is mounted upon 50 a suitable machine base. Since it is highly desir-

able to be able to accommodate a multiplicity of sizes and heights of bits, the rotor means are preferably movable on their supporting bases to alter the relation of each to the other and with respect to the bit holder. I, therefore, provide means for the manual shifting of one of said rotor means and link mechanism actuated by movement of said first mentioned rotor means to shift the second rotor in correlation to the first. Since the height and gauge of the various sizes of bits follow a definite pattern to which the rotor means can be accommodated this correlation increases the ease and speed with which the milling operations can be conducted.

A movable stop in the path of the swinging bit holder is tied into the shifting movement of the milling cutters so that a shift of them is accompanied by an automatic and correlated shift of the movable stop. This stop member serves to limit the amount of travel of a bit in introducing it to the sharpening milling cutter.

The novel features that I consider characteristic of my invention are set forth with particularity in the appended claims. The invention itself, however, both as to its organization and its method of operation, together with additional objects and advantages thereof, will best be understood from the following description of a specific embodiment when read in connection with the accompanying drawings, in which

Figure 1 is a side elevational view of my bit conditioning machine, with portions omitted for convenience of illustration;

Figure 2 is a fragmentary perspective view of the stop mechanism for the bit holder;

Figure 3 is a plan view of the bit conditioning machine;

Figure 4 is a schematic side view of the bit holder delineating its relation to the movable sharpening miller in the various positions thereof;

Figure 5 is a fragmentary view showing the relation of the bit being gauged to the gauging miller; and

Figure 6 is a fragmentary perspective view of the shiftable rotor mounting means employed in my invention.

A drill bit sharpening and gauging machine, to overcome the defects hereinbefore enumerated, must have at least two distinct characteristics; it must be adjustable in the relation of its parts to accommodate a plurality of sizes and heights of drill bits; and it also must be capable of being adjusted without recourse to highly skilled labor or highly trained mechanics.

Accordingly, a preferred embodiment of my invention, referring to Figures 1 and 3, is constituted by a machine base 11 which provides the rotor mounting table 12 and the upright mounting face 13. Upon the table 12 I provide machine ways 14 with which is associated the slide table 15 for sliding movement in the conventional manner. Movement of the table 15 is here shown as being produced by the rotation of lead screw 16 in the lead nut 17 that is secured to table 15. A hand wheel 18 on the screw facilitates its manual rotation by an operator. It will be seen that rotation of the screw 16 by means of the hand wheel will cause the table to shift in one direction or the other according to the guiding action of the ways 14.

A sharpening motor 20 is secured to table 15 and has the pointed-nose milling cutter 21 secured upon its shaft for rotation therewith upon actuation of the motor.

Also mounted upon the shelf 12 of the machine base and to one side of the travel of motor 20 is the bit or tool holder which comprises the arm 24 that pivots about the axis of shaft 25. 5 In the instant case, the arm 24 is secured to shaft 25 by a key 26. Shaft 25 is journaled in suitable bearing blocks 27 mounted on the machine base. A hand lever 28 attached to one end of the shaft 25 permits manual rocking thereof to swing the bit holder arm in the presentation of bits thereon to the sharpening and gauging millers. It is to be understood that, upon the arm 24, the bit is mounted so that it is rotatable about its axis for the presentation of the various surfaces to be milled to the milling cutters of the machine.

The movement of hand lever 28 is limited, in the direction it travels, when a bit is being presented to the miller 21. This limitation is governed by the stop 30 that is positioned in its path. Stop 30 is here shown as a bar that is rotatably and slidably mounted in the guide 31 pivotally mounted upon standard 32 that is attached to the machine base. The rear end of bar stop 30 is threaded and engaged in the shank of clevis 33 and, by means of hand wheel 34, the length of bar between the clevis and the abutment end of the stop may be varied to meet operating requirements; in other words to adjust the location of the stop in the path of the hand lever.

Once adjusted, the stop is moved in correlation to the movement of the motor 20 through the operation of a linkage which comprises rock shaft 35 mounted in bearing 36 and having lever 37 secured to one end. Lever 37 is pinned to the clevis 33. At the end of rock shaft 35 opposite lever 37 is secured a second lever 38 having slot 39. An arm 40 carried by the motor 20 is cooperatively attached by pin 41 in slot 39 to lever 38. Since the motor 20 slides in a fixed plane and since the shaft 35 is mounted to rock about a fixed axis, the operation of pin 41 in slot 39 is that of a lost-motion connection to eliminate binding in the operation of the linkage system.

The miller wheel 21 is mounted at one end of the path described by the bit when the latter is moved by the arm 24. At the other end of this arcuate path is the gauge mill wheel 44 which is here shown as being shaped like a truncated cone and has cutting teeth on the conical face whose bit contacting face portion is designated 45. To rotate miller 44, I employ motor 46, the shaft 47 of which receives and is secured to the hub of the miller.

A motor mounting plate 48 is secured on the upright mounting face 13 of the machine base and pivots about pin 49. An ear 50 on plate 48 is adapted to receive the clevis 51 to which is attached link 52 that has at its rear end clevis 53.

On or near the rear of table 12 is provided a pivot base 54 that supports pivot pin 55 about which rotates or swings the lever 56. Pin 55 forms an intermediate fulcrum for lever 56 which at one end is attached to clevis 53 and at the other end has a lost-motion pivotal connection with ear 57 on the slidable motor base 15.

Shifting movement of base 15 is translated into a correlated movement of base 48 through the above described mechanism. Assuming that base 15 is moved in a direction that is away from hand wheel 18, the lever 56 is swung about pivot 55 and pressure is exerted upon the link

52 to swing plate 48 about its pivot 49. In this instance the mill wheels carried by the motors mounted upon the two bases will be moved apart so that a longer arcuate path may be described by a bit presented thereto. Also, it can be seen, the angle at which the axis of rotation of the miller wheel 44 is disposed is more divergent from the vertical than previously and, consequently, the bit-engaging portion of the sloping face 45 of wheel 44 is brought closer to the horizontal.

Should the base 15 be drawn toward hand wheel 18, the operation of lever 56 and link 52 is to draw the motor and its shaft into a more erect position and the bit-engaging portion of the sloping face 45 of the miller wheel 44 diverges more from the horizontal than previously. This function is schematically suggested in Figures 4 and 5 where, in solid lines, the wheels 21 and 44 are shown in a raised position and in dotted lines two of the lower positions are depicted.

The pivoted base 48 may be locked to the mounting face 13 of the machine base on occasion. For this purpose, I form curved slots 60 through the base plate and bolts 61 passing therethrough and into the machine base. By having the radius of curvature of the slots coincide with the axis of the pivot 49 it is possible for the plate to swing easily when the bolts are loosened and without interference therefrom.

In the gauging operation the operator, who is normally positioned so the gauging motor is to his right side, draws the hand lever 28 toward him and down. At the same time the arm 24 and the bit thereon swings in like manner until the faces of the bit to be surfaced on face 45 effect contact. By means not shown here and forming no part of the present invention, but which appears in detail in my Patent No. 2,268,714, issued January 6, 1942, and the pending patent application, Serial No. 457,563, filed September 7, 1942, the bit may be clamped to the bit arm and be rotated thereon. Or this operation may be performed by rotating the bit on the arm 24 by means of tongs or like implements.

In Figures 4 and 5 the sharpening miller 21 and the gauging miller 44 are shown on the sheet in their approximate relation as they would appear on a machine, the solid line showing of the two views suggesting one setting of the two elements. The dashed lines of the two views suggest the relative movement of the two millers for another setting and the dot-dash showings in the two figures indicate a third setting of the mill wheels.

In the case of the reconditioning of worn rock drill bits, a use for which my invention is particularly adaptable, it is generally true that the height and gauge diameter of the bit decreases with each dulling. When a bit is new and sharp its height and gauge diameter are substantially the same, although the bit teeth have the shape of wings which extend outside the cylindrical mass of the bit itself. In the early sharpenings of such bits the under cut or angle of the gauged face may be at a fairly obtuse angle from the axis of the bit, while in later sharpening the gauge face more nearly approaches parallelism with the axis, since the wings are being cut away each time that the bit is sharpened and gauged. For this reason a bit that has been dulled only once and while it still has much of its original height is preferably sharpened while miller 21 is set at the solid

line position of Figure 4 and gauged at the point of the solid line position of miller 44 in Figure 5. As the bit heights decrease and the diameter diminishes, the miller 21 is moved to one of the dotted line positions and the miller 44 through the action of the link system shifts automatically to a corresponding position of its series. Thus it can be seen that all that an operator need do, once the machine has been set in operation and the various parts properly adjusted, is to set his mill wheel 21 to the height of the bit to be sharpened and the gauge wheel will automatically be set to the proper angle for gauge cutting.

Although I have shown and described certain specific embodiments of my invention, I am fully aware that many modifications thereof are possible. My invention, therefore, is not to be restricted except insofar as is necessitated by the prior art and by the spirit of the appended claims.

I claim:

1. In a drill bit sharpening and gauging machine, the combination, comprising: a bit holder arm adapted by a pivotal mounting to swing a bit in an upright arcuate path, a sharpening miller movably supported in the path of such a bit, a gauging miller movably supported in the same path, and reverse direction link means between said sharpening miller and said gauging miller whereby movement of one of said millers is translated into a correlated shift of the other miller to vary the angle of reception of the contacting faces of the millers when a bit is presented thereto.

2. In a drill bit sharpening and gauging machine, the combination, comprising: bit sharpening means mounted for shifting movement, bit gauging means mounted for shifting movement, means for presenting a bit to said sharpening and to said gauging means, a movable stop to limit the degree to which a bit may be presented to the sharpening means, link means operable between said sharpening and gauging means whereby by shifting movement of one of said means is translated into a correlated shift of the other of said means, and means actuated by shifting movement of the sharpening means to move said stop in relation to the sharpening means.

3. In a drill bit sharpening and gauging machine, the combination, comprising: a machine base, a table slidably shiftable upon said base, means for shifting said table on occasion, rotor means having a sharpening miller and mounted on said base, a base plate pivotally shiftable upon said base, rotor means having a gauging miller and mounted on said base plate, means for presenting a bit to said sharpening and gauging millers, and link means operable upon movement of said slidtable table to shift said base plate about its pivot.

4. In a drill bit sharpening and gauging machine, the combination, comprising: a machine base, a table slidably shiftable upon said base and supporting rotor means and a sharpening miller, a swingable bit holder arm pivotally mounted to present a bit to said sharpening miller, a base plate pivotally shiftable upon said base and supporting rotor means having a gauging miller in the path described by a bit swung by the bit holder arm, and link means operable upon movement of said slidtable table to shift said base plate about its pivot so that the gauging miller carried thereby moves in a direction opposite to the direction of movement of the sharpening miller.

5. A drill bit sharpening and gauging machine, comprising: a movable bit sharpening wheel; a movable bit gauging wheel; a bit holder arm; a pivot for swingably mounting said bit holder arm for movement in an arcuate path for presenting a bit carried thereon alternately to each of said wheels; said sharpening wheel being reciprocally movable relative said pivot while maintaining substantially constant the cutting face angle of

contact with bits of varying heights; said gauging wheel being movable to vary the angle of contact of its cutting face with various height bits; and a link means between said wheels operable when one wheel is moved, to accommodate bits of various heights, to move the other wheel.

JAMES F. McCARTHY, JR.
